7 Claims. (Cl. 328—110)

This invention relates to circuit apparatus for separating relatively short voltage pulses from long voltage pedestals on which they are superimposed. More particularly, the invention relates to apparatus for not only separating the aforesaid short pulses, but also for converting all of the separated pulses to one polarity.

The present invention has as its principal object the provision of electrical circuitry for separating intelligence signals in the form of voltage pulses from a square wave signal on which they are superimposed. The invention has application in installations where, for example, an electron-optics device scans an image of the surface of a bright object having areas of greater or lesser brightness thereon. In such an arrangement, a relatively long voltage pedestal will be produced each time the electron beam scans the image of the surface of the bright object. Superimposed upon this voltage pedestal are positive and negative short voltage pulses produced when the electron beam of the electron-optics device scans the image of brighter and darker areas, respectively. In order to utilize the intelligence regarding the bright and dark areas, it is necessary to separate the aforesaid short voltage pulses from the pedestals on which they are superimposed. As will hereinafter become apparent, this is readily and effectively accomplished in accordance with the present invention.

Another object of the invention resides in the provision of apparatus for converting to one polarity all of the aforesaid positive and negative voltage pulses superimposed upon the voltage pulses of a square wave signal.

The above and other objects and features of the invention will become readily apparent from the following detailed description taken in connection with the accompanying drawings which form a part of this specification and in which:

Figure 1 is a schematic circuit diagram of a preferred embodiment of the invention; and

Figure 2 illustrates wave forms appearing at various points in the circuit of Figure 1.

Referring now to Figs. 1 and 2, output signals from a signal source, generally indicated at 10, are applied to each of three signal channels 12, 14 and 16. The output of signal source 10 will appear as wave form A in Fig. 2 and comprises a series of voltage pedestals or square waves having short positive and negative pulses 18 and 20 superimposed thereon. Although only two pulses are shown in the wave form A, it should be understood that the number of short pulses may vary, depending upon circumstances. In addition, the pulses may either be of alternate polarities as shown, or all of one polarity.

In channel 12 wave form A is fed through an amplifier 22 and differentiator 24 to a pulse separation circuit 26. As is well known to those skilled in the art, differentiator 24 is a circuit in which the voltage amplitude at the output is proportional at any instant to the rate of change of voltage amplitude in the input. The voltage wave form appearing at the output of the differentiator will, therefore, be a series of sharp voltage pulses which oc-

2

cur in time at the points where the input signal A changes from one voltage level to another. This wave form is shown as wave form B in Fig. 2. As the voltage changes in a positive direction, the sharp pulse produced by the differentiator is also positive, and thus a sharp positive voltage pulse is produced at the leading edge of each pedestal and each positive pulse in the original wave form. On the other hand, a sharp negative pulse is produced at the trailing edge of each positive pulse or pedestal. In the case of negative pulses such as pulse 20, however, the situation is reversed. That is, a negative sharp pulse is produced at the leading edge while a sharp positive pulse is produced at the trailing edge.

The pulse separation circuit 26 includes a pair of diodes 28 and 30, each having one of its electrodes connected to ground. It will be noted that the polarities of these diodes are reversed. Thus, diode 28 will pass positive pulses in wave form B to lead 32; whereas, diode 30 will pass negative pulses in the wave form to lead 34. The signals appearing on leads 32 and 34 are, therefore, the positive and negative halves, respectively, of wave form B. The sharp voltage pulses on lead 34 are applied to an amplifier 36. Since the original signal fed to this amplifier had only negative pulses therein, the pulses appearing at its output will be inverted in phase and of positive polarity. In a similar manner, positive pulses passing through diode 28 and appearing on lead 32 are fed to an amplifier 38 where they are inverted in phase. The output of amplifier 38 will, therefore, be a series of negative sharp voltage pulses. Consequently, these pulses are passed through a phase inverter 40 which again converts them to positive pulses. The positive pulses at the outputs of circuits 36 and 40 are then fed to a mixer 42. The output of mixer 42 will appear as wave form C in Fig. 2 where a sharp spiked pulse appears at the leading and trailing edge of each pulse or pedestal in wave form A. In this case, however, all of the spiked pulses are of the same polarity (namely, negative) because of the combined action of circuits 26, 36, 38, 40 and 42. The output of mixer 42, appearing as wave form C, is then fed through amplifier 44 and phase inverter 46 in channel 12 to a late gate circuit 48 in channel 14.

The signal from source 10 in channel 14 is first fed through an amplifier 50 and cathode follower 52 to a delay line 54 which will delay the original wave form A by one-half microsecond. Thus, the output of the delay line 54 will appear as wave form D in Fig. 2. The output of delay line 54 is applied through capacitor 55 and resistor 58 to the grid of one of two triode tubes 60 and 62 in a Schmitt trigger circuit 56. It will be noted that the cathodes of triodes 60 and 62 in Schmitt trigger circuit 56 are connected to ground through a common resistor 64. Furthermore, the anode of triode 60 is connected to the grid of triode 62 through the parallel combination of capacitor 66 and resistor 68.

Under normal conditions, triode 62 will conduct while triode 60 is cut off. However, whenever the voltage level of wave form D at the output of delay line 54 rises above level 70 indicated in Fig. 2, conduction will be initiated in triode 60. This action will cut off triode 62 because of the fall in the plate voltage of triode 60 which is coupled to the grid of triode 62 through elements 66 and 68. Triode 60 will continue to conduct until the voltage level of the pulse in wave form D falls below that indicated by the numeral 70, at which time it will cut off and triode 62 will again conduct. The output appearing at the plate of triode 62 is, therefore, a series of positive square wave pulses each of which has a pulse width equal to the width of the voltage pedestals in wave form D. The output of Schmitt trigger 56 thus appears as wave form E in Fig. 2. This wave form is fed through a phase inverter 72 to the late gate circuit 48. It should be remembered

that the switching action at level 70 is very precipitous due to the regenerative action of the common cathode resistor 64.

Signals will appear at the output of late gate circuit 48 only upon coincidence of pulses in wave form E at the output of Schmitt trigger 56 with pulses in wave form C at the output of phase inverter 46. It will be noted that since wave forms D and E are delayed by one-half microsecond with respect to the original wave form A, the spiked pulse 74 in wave form C due to the leading edge of each pedestal in wave form A does not coincide in time with the pulses in wave form E. Consequently, the pulses 74 will be eliminated in late gate 48 to produce wave form F in Fig. 2 wherein all but pulses 74 remain.

The output of late gate circuit 48 is then applied through a second one-half microsecond delay line 76 and amplifier 78 to an early gate circuit 80 in channel 16. The output of amplifier 78, therefore, will appear as wave form G which is identical to wave form F except that it has been delayed by one-half microsecond.

Reverting again to the signal source 10, its output is also fed as wave form A in Fig. 2 to channel 16 which includes a Schmitt trigger circuit 82 similar to circuit 56 already described. Thus, the output of the Schmitt trigger circuit 82 will appear as wave form H in Fig. 2 wherein a pulse is produced for each pedestal in wave form A, these pulses having the same pulse width and phase position as the original pedestals. After passing through phase inverter 84, the wave form H is applied to the early gate circuit 80 which will pass signals to amplifier 86 only upon coincidence of pulses in wave form H with those in wave form G. It can be seen from an inspection of Fig. 2 that since wave form G has been delayed by one-half microsecond, the sharp voltage pulse 88 due to the trailing edge of each pedestal in the original wave form A does not coincide with a pulse in wave form H. Consequently, these pulses will be eliminated at the output of early gate circuit 80 to produce wave form I wherein only the sharp spiked pulses due to the leading and trailing edges of short pulses 18 and 20 in the original wave form A remain. The one-half microsecond delay illustrated above is, of course, not critical, it being necessary only that the delay is sufficient to eliminate pulses 18 and 20. Actually, the delay should be kept as small as possible in order to prevent the elimination of intelligence pulses which are superimposed on the pedestal close to its leading and trailing edges.

The pulses in wave form I are then fed to a flip-flop circuit, generally indicated at 90, which includes two triode tubes 92 and 94. It can be seen that the cathodes of triodes 92 and 94 are both connected to ground through a single resistor 96 as were the cathodes of triodes 60 and 62 in Schmitt trigger 56. The plate of triode 94 is connected to a B+ voltage source through resistor 98; whereas the plate of triode 92 is connected to the same source of voltage through resistor 100. The grid of triode 92 is connected to ground through resistor 102 and to the B+ voltage source through resistors 104 and 98, with resistor 104 being bypassed by capacitor 106. In a similar manner, the grid of triode 94 is connected to ground through resistor 108 and to the B+ voltage source through resistors 110 and 100, with resistor 110 being bypassed by capacitor 112. It will be noted that the plate of triode 92 is connected to the grid of triode 94 through resistor 110 and capacitor 112. Likewise, the plate of triode 94 is connected to the grid of triode 92 through resistor 104 and capacitor 106.

When a source of anode voltage is applied as to the flip-flop circuit, current will tend to flow in the plate circuits of triodes 92 and 94. If the two halves of the circuit are identical, the currents will be nearly equal at first. However, a perfect balance is always impossible; and as will become apparent from the following description, means are provided to insure that one of the tubes

initially conducts more heavily than the other. This initial difference in conduction brings about a cumulative increase in the end balance as follows: It will be assumed that triode 92 initially conducts more heavily than triode 94. The increased current in triode 92 causes an increase in the voltage drop across resistor 100; and, thus, a decrease in the plate voltage of tube 92. Because of the connection between the plate of triode 92 and the grid of triode 94, the decrease in the plate voltage of triode 92 is accompanied by a decrease in the grid voltage of triode 94. Thus, an increase in the plate current of tube 92 must be accompanied by a decrease in the plate current of tube 94 since its grid is now driven negative. Moreover, the decrease of plate current through tube 94 causes an increase in grid voltage of triode 92 and, consequently, results in a further increase of plate current through triode 92. In this manner, a slight initial unbalance sets up a cumulative or regenerative switching action which reduces the plate current of tube 94 to zero and increases the plate current of tube 92 to a maximum. Though described as if it occurred slowly, this switching action occurs with extreme rapidity—in a fraction of a microsecond in most flip-flop circuits.

The pulses in wave form I from amplifier 86 are applied to the grids of triodes 92 and 94 through diodes 114 and 116. If triode 92 is conducting, these pulses, which are negative at the output of amplifier 86, cut off triode 92. This causes a regenerative switching action in which, while triode 92 cuts off, triode 94 conducts. Furthermore, triode 94 will continue to conduct until the next pulse in wave form I is received. This pulse will now cut off triode 94 and will again initiate conduction in triode 92. This results in a pulse being produced between the sharp spiked pulses in wave form I which are due to the leading and trailing edges of each short pulse 18, 20 in the original wave form A. Thus, the output of the flip-flop circuit on the anode of triode 94 and resistor 118 will appear as wave form J in Fig. 2. This wave form, in effect, constitutes the original short pulses in wave form A which have been converted to one polarity and have been separated from the voltage pedestals on which they were superimposed.

The present invention thus provides a means for separating the pulses 18 and 20 from the remainder of the signal in wave form A and for converting these pulses to one polarity. Although the invention has been shown in connection with a certain specific embodiment, it will be readily apparent to those skilled in the art that various changes in form and arrangement of parts may be made to suit requirements without departing from the spirit and scope of the invention.

We claim as our invention:

1. In combination with means for producing a train of relatively long voltage pulses having short voltage pulses superimposed thereon, circuit means for separating the short pulses from the relatively long pulses comprising, in combination, apparatus responsive to said train of voltage pulses for producing a spiked pulse at the leading and trailing edge of each pulse in said train of pulses, means for eliminating the spiked pulses due to the leading and trailing edges of the relatively long pulses in said train of pulses, and means responsive to the output of said last-named means for producing a pulse between the spiked pulses at the leading and trailing edges of each short pulse in said train of pulses.

2. In combination with means for producing a train of relatively long voltage pulses having short voltage pulses superimposed thereon, circuit means for separating the short pulses from the relatively long pulses comprising, in combination, a differentiator responsive to said train of voltage pulses for producing a spiked pulse at the leading and trailing edge of each pulse in said train of pulses, gating apparatus responsive to the original train of pulses for eliminating the spiked pulses due to the

leading and trailing edges of the relatively long pulses in said train of pulses, and a flip-flop circuit responsive to the output of said gating apparatus for producing a pulse between the spiked pulses at the leading and trailing edges of each short pulse in said train of pulses.

3. In combination with means for producing a train of relatively long voltage pulses having positive and negative short voltage pulses superimposed thereon, circuit means for separating the short pulses from the relatively long pulses and for converting the short pulses to one polarity comprising, in combination, apparatus responsive to said train of voltage pulses for producing a spiked positive pulse at one edge of each pulse in said train of pulses and a spiked negative pulse at the other edge of each pulse in said train of pulses, means for converting all of said spiked pulses to one polarity, apparatus for eliminating the spiked pulses due to the leading and trailing edges of each relatively long pulse in said train of pulses, and multivibrator means responsive to the output of said last-named apparatus for producing a pulse between the spiked pulses at the leading and trailing edges of each short pulse in said train of pulses.

4. In combination with means for producing a train of relatively long voltage pulses having positive and negative short voltage pulses superimposed thereon, circuit means for separating the short pulses from the relatively long pulses and for converting the short pulses to one polarity, comprising, in combination, apparatus responsive to said train of voltage pulses for producing a spiked positive pulse at one edge of each pulse in said train of pulses and a spiked negative pulse at the other edge of each pulse in said train of pulses, means for separating the spiked negative pulses from the spiked positive pulses, means for inverting the phase of said spiked negative pulses, a device for recombining the separated spiked pulses to produce a resultant signal in which all spiked pulses are of one polarity, apparatus responsive to the output of said device for eliminating the spiked pulses due to the leading and trailing edges of each relatively long pulse in said train of pulses, and apparatus responsive to the output of said last-named apparatus for producing a pulse between the spiked pulses at the leading and trailing edges of each short pulse in said train of pulses.

5. In combination with means for producing a train of relatively long voltage pulses having positive and negative short voltage pulses superimposed thereon, circuit apparatus for separating the short pulses from the relatively long pulses and for converting the short pulses to one polarity comprising, in combination, a differentiator responsive to said train of voltage pulses for producing a positive spiked pulse at one edge of each pulse in said train of pulses and a negative spiked pulse at the other edge of each pulse in the train, means for converting all of said spiked pulses to one polarity, means responsive to said train of pulses for producing first and second gating signals, means for delaying the first gating signal by a predetermined amount, first means for gating said spiked pulses with the delayed first gating signal whereby the spiked pulses due to the leading edges of the relatively long pulses in said train are eliminated, means for delaying the spiked pulses after passing through said first gating means, second means for gating the delayed spiked pulses with said second gating signal whereby the spiked pulses due to the trailing edges of the relatively long pulses in said train are eliminated, and a device responsive to the spiked pulses after passing through the second gating means for producing a third pulsed signal in which a pulse is formed between the leading and trailing edges of each short pulse in the original train of pulses.

6. In combination with means for producing a train

of relatively long voltage pulses having positive and negative short voltage pulses superimposed thereon, circuit apparatus for separating the short pulses from the relatively long pulses and for converting the short pulses to

- 5 one polarity comprising, in combination, a differentiator responsive to said train of voltage pulses for producing a positive spiked pulse at one edge of each pulse in said train of pulses and a negative spiked pulse at the other edge of each pulse in the train, means for converting all of said spiked pulses to one polarity, means responsive to said train of pulses for producing first and second pulsed gating signals in which the pulses have the same pulse width and recurrence frequency as the relatively long voltage pulses in said train of pulses, means for delaying the first gating signal by a predetermined amount, first means for gating said spiked pulses with the delayed first gating signal whereby the spiked pulses due to the leading edges of the relatively long pulses in said train are eliminated, means for delaying the spiked pulses after passing through said first gating means, second means for gating the delayed spiked pulses with said second gating signal whereby the spiked pulses due to the trailing edges of the relatively long pulses in said train are eliminated, and a device responsive to the spiked pulses after passing through the second gating means for producing a third pulsed signal in which a pulse is formed between the leading and trailing edges of each short pulse in the original train of pulses.

7. In combination with means for producing a train 30 of relatively long voltage pulses having positive and negative short voltage pulses superimposed thereon, circuit means for separating the short pulses from the relatively long pulses and for converting the short pulses to one polarity comprising, in combination, first, second and third signal channels adapted for connection to said train of pulses, a differentiator in said first channel for producing a positive spiked pulse at one edge of each pulse in said train of pulses and a spiked negative pulse at the other edge of each pulse in the train, means in said first 35 channel for converting all of said spiked pulses to one polarity, first means in said second channel for delaying said train of pulses by a predetermined amount, further means in said second channel and responsive to the output of said first delaying means for producing a first pulsed gating signal in which the pulses have the same pulse width and recurrence frequency as the relatively long pulses in said train of pulses, a first device in said second channel for gating the output of said first 40 channel with said first gating signal, means for delaying the output of said first gating device by a predetermined amount, means in said third channel and responsive to said train of voltage pulses for producing a second pulsed gating signal in which the pulses have the same pulse width and recurrence frequency as the relatively long pulses in said train of pulses, a second device in said third channel for gating the delayed output of said first gating device with said second gating signal, and a flip-flop circuit in said third channel and responsive 45 to the output of said second gating device for producing a pulse between the spiked pulses formed by the leading and trailing edges of each short pulse in the original train of pulses.
